ORNAMENTAL CHAIN

Ferdinand Armbrust, Hoxsie, R. I., assignor to Armbrust Chain Corporation, a corporation of Rhode Island

Application November 28, 1952, Serial No. 22,489

Term of patent 14 years

(Cl. D45—16)

To all whom it may concern:

Be it known that I, Ferdinand Armbrust, a citizen of the United States, residing at Hoxsie, State of Rhode Island, have invented a new, original, and ornamental Design for an Ornamental Chain, of which the following is a specification, reference being had to the accompanying drawing, forming a part hereof.

In the drawing,

Fig. 1 is a top plan view of an ornamental chain showing my new design;

Fig. 2 is a side elevational view thereof, and

Fig. 3 is a perspective view of one of the links thereof.

I claim:

The ornamental design for an ornamental chain, as shown.
